UNITED STATES PATENT OFFICE

HARRY DENTON PIPER, OF CHICAGO, ILLINOIS, ASSIGNOR TO WESTERN ELECTRIC COMPANY, INCORPORATED, OF NEW YORK, N. Y., A CORPORATION OF NEW YORK

METHOD OF AND AN APPARATUS FOR WORKING MATERIAL

Application filed February 28, 1927. Serial No. 171,711.

This invention relates to a method of and an apparatus for working material, and more particularly to a method of and an apparatus for producing strip material.

One manner of increasing the inductance of a conductor employed for the transmission of alternating current is to wrap the conductor spirally with a layer of wire or tape of magnetic material. This method is known in the art as continuous inductive loading as distinguished from lump loading by means of coils distributed along the conductor. Until recently iron has been considered to be the only material available for continuous loading. It has been discovered, however, that a more suitable material may be produced in the form of an alloy of nickel and iron. This material is known as permalloy. When the two metals are in proper proportions and the alloy is given proper heat treatment, a material having very high permeability at low magnetizing force is obtained. The ingredients of the magnetic alloy, permalloy for example, are first fused together in an induction furnace, then molded into the form of a bar or rod, and may then be worked or drawn down preferably into the form of a wire of desired diameter and hardness. If the loading material is to be in the form of a tape or strip, which is one of the preferred forms, the wire is given a plurality of passes between a pair of pressure rolls and flattened into a very thin strip. To provide for a predetermined uniform inductance throughout the length of the loaded conductor it is necessary that the permalloy strip be of substantially uniform dimensions and characteristics throughout its length. Heretofore in the production of permalloy strip material, particularly where a drawn wire is worked to form a flat strip, it has been difficult to produce strips having predetermined uniform dimensions and characteristics throughout their length. One of the reasons for this is that the drawn wire is not always of uniform diameter along its entire length, due to various factors, one of which is the gradual wear on the drawing dies. Also during the subsequent annealing process the wire may not be uniformly an-

nealed throughout its entire length, due to different causes, thus resulting in various degrees of hardness in the wire. These defects in the drawn and annealed wire in the subsequent forming thereof into a very thin tape or strip produces at times a product which is not of uniform dimensions and characteristics throughout its length. For a full disclosure of the metallurgical and electrical characteristics of this alloy and its heat treatment, reference is made to Patents 1,586,884 to G. W. Elmen, June 1, 1926, 1,586,874 to O. E. Buckley, June 1, 1926, and 1,586,887 to G. W. Elmen, June 1, 1926.

The objects of this invention are to provide an improved method of and an improved apparatus for producing from material of varying dimensions and characteristics strip material having predetermined uniform dimensions and uniform characteristics throughout its length.

In accordance with the general features of this invention as practiced in one embodiment thereof for the production of strip permalloy, a plurality of wires composed of such material are first subjected to pressure sufficient to flatten them into very thin strips. Thereafter the strips are simultaneously drawn between sets of oppositely disposed rolls individual to each strip, whereby the opposite edges of the strip are subjected to lateral pressure, depending on the ultimate width desired and the amount of reduction in thickness thereof due to the lateral surfaces of the strips being thereafter subjected to pressure. Such an arrangement enables the simultaneous production of a plurality of strips having predetermined uniform dimensions and uniform characteristics throughout their length, which are very essential in the case of continuous loading of signaling conductors.

Other objects and advantages of this invention will more fully appear from the following detailed description taken in connection with the accompanying drawings, in which

Fig. 1 is a diagrammatic plan view of an apparatus embodying the features of this in-

100

vention and whereby the improved method may be practiced;

Fig. 2 is a side view thereof;

Fig. 3 is an enlarged fragmentary plan view of a portion of Fig. 1 showing a unit comprising the strip edging and molding rolls and associated rolls for preventing buckling of the strip;

Fig. 4 is a section on the line 4—4 thereof;

Fig. 5 is a greatly enlarged fragmentary plan view of the central portion of Fig. 3;

Fig. 6 is an enlarged plan view of a portion of Fig. 1 showing the strip guides associated with the pressure rolls at the entrance 15 and exit sides of the rolls;

Fig. 7 is a longitudinal section therethrough, and

Fig. 8 is an enlarged fragmentary section on the line 8—8 of Fig. 7.

Referring now to the drawings in which like numerals are employed to designate similar parts throughout the several views, Figs. 1 and 2 illustrate diagrammatically an apparatus designed to simultaneously produce 25 six identical flat strips 10 of predetermined uniform dimensions and uniform characteristics throughout their entire length, which includes a rolling mill comprising the usual frame 11 including a pair of parallel, power 30 driven rolls 12. The rolls 12 are shaped with journals 13 on either end thereof, which turn in suitable bearings 14 carried by the frame 11 and upon one end terminate in a pair of shafts 15 and 16 by means of which 35 the rolls may be driven from a suitable source of power (not shown). The rolls 12 are positioned with respect to each other by means of adjusting screws 19 which engage each one of the bearings 14 associated with the 40 upper roll 12 as indicated in Fig. 2 for adjusting the pressure exerted upon the strips passing between the rolls, separating springs 20 positioned between the bearings tending to separate the rolls upon releasing the 45 screws.

Each of the strips 10 to be worked, which strips have been suitably flattened by successive passes between pressure rolls (not shown) to very thin strips, for instance .008 50 of an inch in thickness from wire of a suitable diameter, is carried in coil form upon a supply reel 21 (Fig. 2) mounted upon a standard 22 fixed to the floor. From its associated reel 21 each of the strips 10 is drawn 55 upwardly and through a stationary guide block 23 which directs the strip between two pair of oppositely disposed rolls 26 and 27 each journaled in a carriage 28 in turn reciprocally mounted in a frame 29. The carriages 28 are each fixed to a micrometer screw 60 to permit an accurate adjustment of the rolls 26 and 27 which engage opposite surfaces of the strip 10. As clearly illustrated in Figs. 3, 4 and 5 the rolls 26 bear against 65 the opposite narrow edges of the strip and

are adjusted to subject the strip to sufficient pressure to form or mold the strip during its passage therebetween into a strip provided with even edges and a uniform width throughout its length, as will be referred to again hereinafter. It is to be noted that the pressure exerted upon the strip 10 from the rolls 26 and 12 is sufficient to mold the strip to such an extent that the characteristics thereof will be uniform throughout its entire length, thus remedying the conditions at times occurring in the drawn wire due to the non-uniform annealing thereof. The rolls 27 are positioned adjacent the opposite wide faces of the strip with just sufficient clearance therebetween to eliminate friction for the purpose of preventing buckling or distortion of the strip during its subjection to lateral pressure by the molding rolls 26. Referring to Fig. 5 it will be noted that the rolls 26 are provided with a plurality of annular channels 33 having beveled opposite walls 34, which formation serves to prevent the strip 10 from moving laterally thereon, while a plurality of channels is provided so that when one channel becomes worn the rolls may be adjusted to align another channel in position, thus making it unnecessary to replace the roll. The beveled opposite walls 34 of the channels are of usual construction to prevent the formation of what is generally termed "fins" at opposite sides of each of the edges of the strip and to reduce surface friction. Suitable means (not shown) is provided for adjusting the rolls 26 so that the peripheral working face of the channels 33 will parallelly engage the edge of the strip 10.

Upon passing from between the rolls 26 and 27 each of the strips 10 is guided over and under grooved rolls 35 and thence through a guide mechanism 36, shown in enlarged detail in Figs. 6, 7 and 8, which serves to guide the strips 10 along a horizontal plane equidistant the axes of the rolls 12 and under a suitable tension.

The guide mechanism 36 comprises a block 39 which extends almost up to the peripheral surface of the rolls 12 upon the entrance side thereof, as clearly shown in Fig. 7 and is clamped as indicated at 40 to a table 41 carried upon the frame 11 of the mill. Formed in the upper surface of the block 39 at either end thereof is a plurality of longitudinally extending channels 42 equal in number to the strips 10 being worked for preventing lateral movement of the strips as they pass to the rolls 12. Supported upon the upper surface of the block 39 is a plate 43 provided at either end with shouldered slots 44 corresponding in number to the channels 42 in the block 39 and aligned vertically therewith, as clearly shown in Fig. 8. Reciprocally mounted for vertical movement in each of the slots 44 is a shoe 45, the lower end of

which engages the upper surface of the strip 10 being advanced through the channel 42. The shoes 45 are urged downwardly with sufficient force to provide a suitable tension or drag upon the strips as they enter between the rolls 12 by leaf springs 46 bearing at one end upon the upper surface of the shoes 45 with their opposite ends fixed to the plate 43. The plate 43 is secured in operative position upon the block 39 by a cam wheel 47 journaled upon a shaft 48 supported at opposite ends in ears 49 formed upon the table 41. A handle 52 is provided for rotating the cam wheel 47, which as shown in the drawings, particularly referring to Fig. 7, has been rotated counter-clockwise to clamp the plate 43 against the block 39, a rotation in a reverse direction it will be apparent will release the plate 43.

Upon the right side of the rolls 12 is a second guide block 53 mounted upon a table 54 in a manner similar to that of the block 39 upon the table 41 and likewise secured to the frame 11 of the mill. Also formed in the block 53 at either end thereof are a plurality of channels 55 similar to the channels 42 of the block 39 which serve to prevent the strips 10 from swerving to one side or the other as they emerge from between the rolls 12. It will be apparent that by means of the grooved rolls 35 and the guide mechanism 36 the thin metal strips 10 are guided under tension practically to the very point of contact with the rolls 12 and buckling or overlapping of the strips between the rolls 26 and 27 and the pressure rolls 12 is minimized. The guide mechanism 36 cooperating with the guide block 53 serves to guide the thin strips 10 to and from the rolls 12 on a horizontal plane intermediate the axes thereof and at right angles thereto, thus eliminating all tendency of the strips being distorted in the rolling operation. The two rolls 12 it is understood should be of exactly the same diameter with their axes positioned parallel and both should be driven at exactly the same speed to secure the best results.

From the guide block 53 each of the strips 10 pass over grooved guide rolls 56 and thence to a suitably driven take-up reel 57 mounted upon a standard 58. The strip is accurately distributed upon the reel 57 by a traversing finger 59 designed to lay the strip close to either head of the reel, the finger being operated back and forth between the heads of the reel by a carriage 60 receiving motion from a suitable source of power (not shown).

In practicing the improved method of producing strip material, particularly permalloy strip material by the apparatus herein described, the strips 10, which, as previously described, have preferably been produced from wire of suitable diameter flattened by a plurality of passes between pressure rolls

and taken up upon the supply reels 21 are threaded through the guide blocks 23, between the two pair of oppositely disposed molding rolls 26 and 27 with the opposite edges of the strips entered within one of the annular channels 33 of each of the rolls 26 and the opposite wide faces of the tapes lying in close association with the oppositely disposed peripheral faces of the rolls 27. Thenceforth the strips are guided to the pressure rolls 12 by means of the grooved rolls 35 and the guide mechanism 36, between the rolls 12, through the guide block 53, over the grooved guide rolls 56 and thence to the take-up reels 57, where in operation the fingers 59 through the reciprocatory movement of the carriage 60 accurately distribute the completed strips upon the reels. Upon the pressure rolls 12 being positioned with their axes in the same plane and set to exert a suitable pressure upon the strip they are set in motion along with the take-up reels 57.

The edging or molding rolls 26 of each unit are adjusted as previously described to exert sufficient pressure upon the narrow opposite edges of the associated strip to produce a strip of uniform width with smooth edges throughout its entire length, the adjustment being such that the lateral pressure exerted upon the opposite edges of the strip molds the strip substantially to its ultimate or desired width. The advancing strip thus acted upon by the rolls 26 passes through the rolls 12, the pressure of which is just sufficient to reduce it to a desired uniform predetermined thickness, the slight excess metal displaced due to this pressure flowing toward the sides of the strip without appreciably increasing the width thereof and taken with the effect produced by the rolls 26, resulting in the production of a strip of metal having a predetermined uniform width and thickness throughout its length and with smooth edges and of uniform characteristics.

During the operation of the apparatus an attendant may measure the width and thickness of the strips as they pass from the guide block 53 and before they reach the take-up reels 57 in any suitable manner, and if the width or thickness thereof falls above maximum or below minimum limits the molding rolls 26 associated with the particular strip are adjusted to provide substantially the desired width of strip, which width will not be appreciably altered in the subsequent subjection of the strip to pressure by the rolls 12 which serve to produce the desired thickness of the strips.

What is claimed is:

1. The method of producing strip material of substantially uniform dimensions and characteristics throughout its length from material of varying dimensions and characteristics, which consists in reducing the width of the material to substantially its ultimate

width and thereafter reducing its thickness without appreciably varying the width thereof to produce a strip of predetermined uniform dimensions and characteristics.

5. 2. The method of producing strip material of substantially uniform dimensions and characteristics throughout its length from material of varying dimensions and characteristics, which consists in subjecting the material to lateral pressure to reduce the width thereof to substantially its ultimate width and immediately thereafter subjecting it to pressure to cause a reduction in its thickness without appreciably varying the width thereof to produce a strip of predetermined uniform dimensions and characteristics.

20. 3. The method of producing strip material of substantially uniform dimensions and characteristics throughout its length from material of varying dimensions and characteristics, which consists in passing the material between a plurality of rolls for subjecting the material to lateral pressure to reduce the width thereof to substantially its ultimate width, and thereafter reducing its thickness without appreciably varying the width thereof to produce a strip of predetermined uniform dimensions.

30. 4. The method of producing strip material of substantially uniform dimensions throughout its length from material of varying dimensions, which consists in continuously passing the material between a plurality of rolls for subjecting the material to lateral pressure 35 to reduce the width thereof to substantially its ultimate width, and contemporaneously therewith subjecting an advanced portion of the strip to pressure by passage between a plurality of rolls to cause a reduction in its thickness without appreciably varying the width thereof to produce a strip of predetermined uniform dimensions.

45. 5. The method of producing strip material of substantially uniform dimensions throughout its length from material of varying dimensions, which consists in reducing the width of the material to substantially its ultimate width and thereafter guiding the strip under tension between a pair of rolls and at 50 right angles to the axes thereof for subjecting it to pressure without appreciably varying the width thereof to produce a strip of predetermined dimensions.

55. 6. The method of cold working a nickel iron alloy strip to produce a strip of substantially uniform thickness and width throughout its length, which consists in reducing the width of the strip to substantially its ultimate width and thereafter reducing its thickness without appreciably varying the width thereof to produce a strip of predetermined uniform dimensions.

60. 7. In an apparatus for producing strip material of substantially uniform dimensions and characteristics throughout its length

from a strip of varying dimensions and characteristics, peripherally channelled rolls for subjecting the opposite lateral edges of the strip to pressure to reduce the width thereof to substantially its ultimate width, the edges 70 of the strip engaging in the channels of the rolls to prevent relative transverse movement therebetween, power driven rolls positioned to receive the strip from the channelled rolls for advancing the strip between the channelled rolls and shaped to reduce the thickness of the strip without appreciably varying the width thereof, and friction means positioned between the channelled rolls and the power driven rolls.

80. 8. In an apparatus for producing strip material of substantially uniform dimensions throughout its length from a strip of varying dimensions, adjustable peripherally channelled rolls for subjecting the opposite lateral edges of the strip to pressure to reduce the width thereof to substantially its ultimate width, the edges of the strip engaging in the channels of the rolls to prevent relative transverse movement therebetween, rolls positioned adjacent opposite sides of the strip to prevent distortion thereof during its subjection to lateral pressure, power driven rolls positioned to receive the strip from the channelled rolls for advancing the strip between the channelled rolls and adapted to reduce the thickness of the strip without appreciably varying the width thereof, and guiding means positioned between the channelled rolls and the power driven rolls.

90. 9. In an apparatus for producing strip material to substantially uniform dimensions throughout its length from a strip of varying dimensions, a pair of channelled rolls for subjecting the opposite lateral edges of the material to pressure to reduce the width thereof to substantially its ultimate width, a pair of individually adjustable rolls positioned adjacent opposite sides of the strip and arranged with their axes in a substantially common plane with the axes of the width reducing rolls to prevent distortion of the strip during the width reducing operation, power driven rolls for advancing the strip between the width reducing rolls and for reducing the thickness of the strip, and guiding means positioned between the channelled rolls and the power driven rolls.

100. 10. In an apparatus for producing strip material, a pair of opposed channelled pressure rolls for reducing the width of the strip and forming the edges thereof, frictional guiding means positioned to receive the strip from the channelled rolls, and means for drawing the strip through the channelled rolls and the guiding means and for simultaneously compressing it at right angles to the direction of the pressure applied by the channelled rolls to thereby reduce its thickness.

11. 11. The method of producing conductor

loading material in strip form of substantially uniform dimensions and characteristics throughout its length from material of varying dimensions and characteristics, which consists in engaging the edges of cold strip material during the advancement thereof to reduce the width of the material to its ultimate determinable width, and thereafter applying pressure to reduce its thickness without appreciably varying the width thereof 10 to present a strip having characteristics essential to the effective use thereof for conductor loading purposes.

In witness whereof, I hereunto subscribe my name this 11th day of February A. D., 15 1927.
